UNITED STATES PATENT OFFICE.

JOHAN F. THIM, OF CHICAGO, ILLINOIS.

CHRONOMETER-ESCAPEMENT.

SPECIFICATION forming part of Letters Patent No. 681,006, dated August 20, 1901.

Application filed March 20, 1901. Serial No. 52,118. (No model.)

To all whom it may concern:

Be it known that I, JOHAN F. THIM, a citizen of the United States, residing at Chicago, in the county of Cook and State of Illinois, 5 have invented certain new and useful Improvements in Chronometer-Escapements, of which the following, when taken in connection with the drawings accompanying and forming a part hereof, is a full and complete 10 description, sufficient to enable those skilled in the art to which it pertains to understand, make, and use the same.

This invention relates to and is an improvement upon the chronometer-escapement invented by Arnold and improved by Earnshaw and Dent.

In the chronometer-escapement embodying this invention the operation is substantially the same as in chronometer-escapements of 20 the kind named heretofore made. As the balance oscillates in the direction of the arrow 1, Figure 1 of the drawings, its unlocking-roller jewel comes in contact with the secondary spring, (usually termed the "gold" spring 25 or the "gold" unlocking-spring,) which is mounted on the detent-spring (sometimes called the "spring-lever") of the escapement and presses or lifts the detent-spring, so that its locking-jewel is freed from the tooth of 30 the escape-wheel in contact therewith and the impulse-roller jewel receives the impact of another tooth of the escape-wheel and the balance receives its impulse thereby. Further, as the balance returns its unlocking- 35 roller jewel passes the secondary spring (the gold unlocking-spring) without moving the detent-spring, which rests against a stop, such secondary spring being so pliable as to allow the unlocking-roller jewel to pass freely 40 by it. The impulse is therefore in the escapement embodying this invention communicated from the escape-wheel direct to the balance-arbor. It therefore occurs that in the escapement embodying my invention, as 45 well as in the ordinary escapement of the kind named, the stroke which moves the detent-spring withdraws the locking-jewel (or detent) from the tooth of the escape-wheel, and at the same time that this tooth escapes 50 another tooth of such escape-wheel strikes a pallet (the impulse-roller jewel) on the arbor

of the balance and restores to the balance-wheel the force lost during a vibration.

In chronometer-escapements of the kind named as the same have been heretofore constructed the blow from the tooth of the escape-wheel is received by the detent-spring striking the locking-jewel of such detent-spring in a direction toward the blade or spring of such detent-spring and tends to compress or buckle such blade or spring portion of such detent-spring, and, further, the escape-wheel is not open to observation in the operation of the same; and the principal object of this invention is to so construct and combine 65 the several parts constituting the escapement that the blow received by the detent-spring shall tend to subject the same to a tension strain, (and not to compression,) such blow being given in a direction from the blade or 70 spring part of the detent-spring, and so tending to pull or stretch such blade or spring part.

In the drawings accompanying and forming a part of this specification and hereinbefore referred to, Fig. 1 is a top plan view of a portion of the upper plate of a chronometer with an escapement embodying this invention attached thereto, but with the balance and the impulse-roller removed from 80 the arbor of the balance; Fig. 2, a vertical sectional view on line 2 2 of Fig. 1 viewed in the direction indicated by the arrows; Fig. 3, a top plan view, on an enlarged scale, of the unlocking-roller and jewel engaging with the 85 gold unlocking-spring of the escapement and of the detent-spring with such parts in the same relative position as shown in Figs. 1 and 2; Fig. 4, a vertical sectional view on line 4 4 of Fig. 1, and Fig. 5 is a perspective view 90 of the impulse-roller and the teeth of the escape-wheel.

A reference-letter applied to indicate a given part is used to designate such part throughout the several views wherever the 95 same appears.

A is the upper plate of the chronometer, having an escapement embodying this invention attached thereto. Plate A is provided with a slot a, in which slot the detent-spring 100 D, hereinafter described, is placed. Slot a is of sufficient width to admit of the necessary

vibratory movement in the detent-spring in the operation thereof.

B is the balance-wheel of the chronometer, and b is the arbor of such balance-wheel.

5 B' is the potance of arbor b and is attached to the under side of plate A by screw b², passing through bridge b' of such potance and into the plate.

B² is the bridge of arbor b and is attached 10 to the plate A by screw b³.

C is the escape-wheel of the chronometer.

C² is a recess in the upper side of the upper plate A, in which recess the escape-wheel C is placed.

15 C' is the arbor of escape-wheel C.

C³ is the escape-wheel bridge, and C⁴ is the screw by which the bridge is attached to the plate A.

D is the detent-spring of the escapement.

20 The detent-spring D comprises the part d', by which such detent-spring is attached to the plate A, as by means of screw D', part d², forming a spring d³, extending from spring part d² to curved part d⁴ and part d⁵. Curved part 25 d⁴ extends around arbor b of the balance-wheel B. Parts d³, d⁴, and d⁵ constitute the body part of the detent-spring D.

d is a jewel or tooth mounted on part d⁵ of detent-spring D.

30 E F are rollers on arbor b of balance-wheel B.

e is a jewel or tooth on unlocking-roller E, and f is a jewel or tooth on impulse-roller F. G is a secondary spring mounted on part d⁵ of 35 detent-spring D, as by screw g. Secondary spring G is ordinarily made of gold and is termed in the art the "gold spring of the escapement" or the "unlocking gold spring."

In the operation of this escapement one of 40 the teeth of the escape-wheel C presses against the locking-jewel or pallet d on detent-spring D, such escape-wheel having at all times a tendency to turn to the right, as is indicated by the arrow 2 in Fig. 1. Any one of the

45 teeth of the escape-wheel being in contact with the locking-jewel d, when the balance-wheel B, unlocking-roller E, and impulse-roller F turn in the direction indicated by the arrow, Fig. 1, so that the unlocking-jewel e comes in contact with the gold unlocking-spring G,

50 such unlocking-jewel or verge-tooth forces the detent-spring F back until the pallet or locking-jewel d is free from engagement with such tooth of the escapement-wheel, at which

55 time the impulse-roller F on arbor b is in position relative to the escape-wheel C, so that the jewel f receives an impulse from one of the teeth of the escape-wheel which is adjacent thereto by the movement of the escape-wheel

60 immediately following the disengagement of the pallet or locking-jewel d from the tooth of the escape-wheel in contact therewith. An impulse is thus given to balance-wheel B in the direction indicated by arrow 1, and this

65 roller F is termed the "impulse-roller." As detent-spring D is forced back or lifted by unlocking-jewel e in the manner above de-

scribed immediately after the locking-jewel d is released from engagement with the tooth of the escapement-wheel C, which is in contact therewith, unlocking-jewel e passes around beyond the end of the gold unlocking-spring G because of the continued movement of the balance-wheel B and arbor b, and the detent-spring D is immediately returned to 75 its initial position by the resilience of spring part d² thereof. Such return of detent-spring D is so quickly made that the pallet or locking-jewel d receives thereon the tooth of the escape-wheel C, succeeding the one last released, as above described. On the return movement of the balance-wheel B, arbor b, unlocking-roller E, and impulse-roller F gold unlocking-spring G is so pliable that the unlocking-jewel e on roller E passes by it without moving the detent-spring D, and the escape-wheel C is then in such position relative to impulse-roller F and the impulse-jewel f thereon that such impulse-jewel passes between the teeth of the escape-wheel adjacent 80 thereto without coming in contact therewith.

The operation of the escapement is, it will be observed, substantially the same as the operation of like escapements of this class as heretofore made, except that the impact received by the pallet or locking-jewel d in the escapement embodying my invention produces tension on spring part d² of the detent-spring, and not compression, as is done in the escapements of this kind heretofore made. 95 Hence I am able to make such spring part d² thinner than the same has heretofore been made. Further, it will be observed that the fulcrum on which the detent-spring turns—that is, spring d² of detent-spring D—is on 100 the same side of the locking-jewel d as is the arbor b, which constitutes the fulcrum of the unlocking-jewel e, and hence engagement of the unlocking-jewel e with gold spring G is less so far as slippage is concerned, and less 105 friction is obtained than is as the same have been heretofore constructed, while in the return movement of the unlocking-jewel the fulcrum of the unlocked gold spring G is substantially in the same relation to the fulcrum 110 of such unlocking-jewel as in the escapements heretofore constructed, and a quicker releasing of the engagement between the unlocking-jewel and the gold spring in the return movement of the unlocking-jewel is obtained.

Having thus described my invention and its operation, what I claim as new, and desire to secure by Letters Patent of the United States, is—

1. In a chronometer-escapement, a detent-spring provided with a spring portion adjacent to the end thereof arranged to be attached to the plate of the chronometer, means for securing a secondary spring to the free end of the detent-spring, a curved portion, 125 arranged to extend around the balance-arbor of the chronometer, between the spring portion of the detent-spring and the point of attachment of the secondary spring thereto,

a locking-jewel mounted on the detent-spring between the curved portion thereof and the point of attachment of the secondary spring thereto, and a secondary spring attached at 5 one end thereof to the free end of the detent-spring; substantially as described.

2. A detent-spring comprising a part arranged to be attached to a plate of a chronometer, a spring portion adjacent to such 10 attachable part, a curved part arranged to extend around a balance-arbor and a body part arranged to have attached thereto a locking-jewel for an escape-wheel and a secondary spring for an unlocking-jewel, in 15 combination with a secondary spring attached at one end thereof to the free end of the detent-spring and extending to the curved portion of such detent-spring, and a locking-jewel, whereby when an unlocking-jewel, of 20 an escapement whereof the detent-spring, the locking-jewel and the secondary spring are elements, lifts the secondary spring in one direction, carrying therewith the detent-spring, the fulcrum of such secondary spring is at 25 the spring end of the detent-spring, and when

such unlocking-jewel lifts the secondary spring in the other direction the fulcrum of the secondary spring is at the other end of the detent-spring; substantially as described.

3. In a chronometer-escapement, a detent-spring, attachable at one end to a chronometer-plate and provided with a spring portion adjacent to the attachable end and a body part adjacent to the spring portion, the attachable portion, the spring portion and the 30 body portion of the spring being integral, in combination with a locking-jewel mounted on the body portion of the detent-spring for an escape-wheel, and a secondary spring attached at one end thereof to the free end of the 35 detent-spring, the secondary spring extending along the detent-spring so that the end thereof operated on by the unlocking-jewel of the escapement is between the locking-jewel and the spring portion of the de- 40 dent-spring; substantially as described.
